UNITED STATES PATENT OFFICE.

ORVILLE M. MORSE, OF JACKSON, MICHIGAN.

DUST-COLLECTOR.

SPECIFICATION forming part of Letters Patent No. 655,635, dated August 7, 1900.

Application filed July 1, 1899. Serial No. 722,570. (No model.)

To all whom it may concern:

Be it known that I, ORVILLE M. MORSE, a citizen of the United States, residing at Jackson, in the county of Jackson and State of Michigan, have invented certain new and useful Improvements in Dust-Collectors, of which the following is a specification, reference being had therein to the accompanying drawings.

10 The invention consists in the construction of a dust-collector embodying a chamber having an air-inlet for the dust-laden air and exit from the chamber, across which are arranged brushes and means for jarring or agitating the brushes and for sweeping up the collected dust.

15 The invention further consists in combining such a dust-collector with an initial dust collector or separator which will collect all but the fine dust and use my improved dust-collector as an attachment thereto for the purpose of collecting this fine dust.

20 The invention further consists in the construction, arrangement, and combination of the various parts, as more fully hereinafter described, and pointed out in the claims.

25 In the drawings, Figure 1 is a sectional perspective view showing my improved dust-collector attached to a dust-separator or dust-collector of the general type shown in my previous patent, No. 403,362, of May 14, 1889. Fig. 2 is a cross-section through the upper part of Fig. 1. Fig. 3 is a detail section illustrating the construction of the vibrating 30 means for the brush or broom sections.

35 I have shown my dust-collector as circular in form and comprising the heads A and B. In this case the head B forms the top of the initial dust-collector, the body of which is 40 formed by the conical wall C, having a discharge D at the lower end and a tangential inlet E for the dust-laden air. The dust, as is well-known, in such momentum dust-collector will be discharged through the exit at 45 the small end of the conical chamber, while the purified air will pass out through an aperture F, arranged centrally in the top or the wall B, as shown in this illustration. In such momentum dust-collector the air passing out 50 through the aperture at the large end will carry with it a considerable amount of im-

palpable dust, so light as not to be affected by the centrifugal action in such momentum dust-collector, and it is to collect the dust in the air passing through this air-exit that I 55 have shown my improved dust-collector applied.

The head A, I have shown secured to a shaft G, which is journaled in suitable bearings in the top of the momentum dust-collector. This is driven by any suitable means— as, for instance, by a worm-gear H on a shaft I, meshing with a worm-wheel J on the upper end of the shaft G. Secured to the edge of the plate or end A are the brushes K, so arranged as to cover the exit from the chamber within. In this construction the brushes K form the entire circumferential wall of the dust-collector. These brushes are preferably formed of a brush-head L, having the 70 pins M slidingly secured through bearings in the top A, with springs N adapted to hold the heads normally in their upper position. These sections are preferably of such length as to extend between the radial plates or dividing-wings O, which are secured to the under side of the head A and extend down into close proximity to the head B, thus dividing the dust-chamber into a series of sectors, as plainly shown in Fig. 2. 75

80 It will be obvious from this description that my dust-collector, as herein shown, consists of a circular chamber, the dust-laden air being delivered thereinto from the aperture F, and that the air may find an exit through that wall thereof which is formed by the brush.

I have found by practical experiment that such dust as comes from the eye of the momentum dust-collector is of such a nature 90 that upon striking an object in its path it will adhere thereto, very much as wet snow adheres to the sides of trees when blown by the wind. I therefore find that with brushes of, for instance, broom-corn or similar material 95 arranged as described in relation to the dust-chamber if the dust-laden air is blown therethrough the dust will adhere to the brush, while the air will find a practically-unobstructed passage through the brush. 100

It will be observed that the brush forms the wall of the dust-collector and that there

is a free and unobstructed exit for the air through that wall and no perforated cloth or wall through which the air must subsequently be passed and which would make a back 5 pressure and to which any small particles of dust which might pass through the brushes would adhere. I find with such a device that the air from the eye of such a momentum dust-collector after passing through my improved dust-collector may be discharged with 10 impunity into the mill.

The radial wings or blades O divide the dust-chamber into a series of compartments, as before described, each one of which extends 15 from the air-inlet section to the brushes at the other end.

In order to clean the brushes of the accumulated dust, I arrange at one point a cover P for a section of the air-inlet passage F, as 20 plainly shown in Fig. 2, this plate being sufficiently long or wide to cut off from the air-inlet opening an entire section of the dust-chamber. While thus cut off, there is of course no air circulation through that chamber 25 and there is formed what I call a "dead-air" chamber therein. While the air circulation is thus shut off or the dead-air chamber is formed I knock or shake the brushes by any suitable means and arrange beneath the 30 same a discharge-spout Q, into which the dust therefrom will pass. The preferable means which I employ for cleaning the brushes of dust consist of a toothed cam R, secured above the machine, which is adapted to be 35 engaged by a pin S, which projects from the brush-head, the brush-head being through the head A in the casing in the travel thereof, as shown at the left hand in Fig. 2 and which is illustrated more particularly in 40 Fig. 3.

It will be seen from this description that through the greater part of the travel the dust from the eye of the momentum dust-collector will rise into my improved dust-collector 45 and pass freely through the brush-walls thereof without any material impeding of the air-current or back pressure on the device and that at one or more points of the operation the air circulation is shut off, and while 50 thus shut off the brushes are cleaned.

I preferably make the plate P adjustable by any suitable means—such, for instance, as the radial slots a, in which clamping-screws may be engaged to clamp the cover or plate in the 55 desired position. This I preferably arrange so that there may be a slot T leading into the eye of the momentum dust-collector at such points therein that there is a draft from the dust-chamber, so that at the time the brushes 60 are shaken or vibrated whatever air pressure or circulation there is is inward, and thereby I prevent any dust from being discharged into the room while the brushes are being cleaned.

I have shown and I preferably employ a 65 flange or strip U around the edge of the head B, extending a slight distance up the brush-

body to insure a tight joint at the lower or free end of the brushes.

What I claim as my invention is—

1. A dust-collector comprising two circular heads, and a circumferentially-arranged brush, a series of imperforate radial division-walls forming a series of chambers, an air-inlet common to all the chambers at the center of one head, means for shutting off the chambers successively, and means for vibrating the brush of the shut-off chamber. 75

2. A dust-collecting device comprising a momentum dust-collector having a tapering body and an apertured head, of a dust-collector applied thereto comprising the head A, radial imperforate division-walls secured thereto, means for rotating the same, a brush formed in sections extending between the edges of the head A and the head of the momentum dust-collector, means for vibrating sections of the brushes, and a dust-spout over which the brushes are vibrated. 80

3. A dust-collecting device comprising a momentum dust-collector having a tapering casing and an apertured head B, of a dust-collector applied to the head and consisting of the head A complementary to the head B, means for rotating the head, a series of circumferentially-arranged brushes secured to 90 the head A and extending to the head B, a series of radial apertures dividing the space between the head into a series of chambers, a cut-off between the opening in the head B and each of the chambers successively during 95 the rotation thereof, and means for vibrating the brush during the cut-off period of such chamber. 100

4. A dust-collecting device comprising a momentum dust-collector, consisting of a casing 105 having an apertured head and a tangential air-inlet, of a dust-collector applied to the aperture in the head and comprising a brush, arranged over the exit therefrom, means for shutting off communication between the exit-opening and the chamber within the casing and connecting it with a reverse-operating draft, and means for vibrating the brush during such shut-off period. 110

5. A dust-collecting device comprising a tapering casing, a tangential inlet for the dust-laden air, a dust-outlet at the small end, an imperforate top having a central aperture for the purified air, an imperforate head above the top of the dust-collector forming a chamber between the two and brushes extending between the head and top through which the air from the chamber last referred to must pass in its exit and means for vibrating or shaking said brushes intermittently. 115

In testimony whereof I affix my signature in presence of two witnesses. 120

ORVILLE M. MORSE.
